UNITED STATES PATENT OFFICE.

FREDERIC E. BERTRAND, OF LYNN, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

SHOE-SEWING MACHINE.

1,405,264.

Specification of Letters Patent. Patented Jan. 31, 1922.

Application filed April 7, 1916, Serial No. 89,560. Renewed June 30, 1921. Serial No. 481,705.

To all whom it may concern:

Be it known that I, FREDERIC E. BERTRAND, a citizen of the United States, residing at Lynn, in the county of Essex and State of Massachusetts, have invented certain new and useful Improvements in Shoe-Sewing Machines; and I do hereby declare the following to be a full, clear, and exact description of the invention, such as will enable others skilled in the art to which it appertains to make and use the same.

The present invention relates to an improvement in shoe sewing machines and more particularly to that type of shoe sewing machines using a curved hook needle adapted for fair stitching mock welts and stitch-down shoes.

The object of the invention is to reorganize and improve the construction of shoe sewing machines in order to produce a more simple, compact and efficient machine especially adapted for high speed, and to this end the present invention consists of a shoe sewing machine provided with the constructions, arrangements and combinations of parts hereinafter described and particularly pointed out in the claims.

In the accompanying drawings illustrating the preferred form of the invention, Figure 1 is a front elevation of a shoe sewing machine embodying the several features of the invention; Fig. 2 is a plan of the machine; Fig. 3 is a side elevation looking from the right; Fig. 4 is a detail of the take-up arm, auxiliary take-up and tension wheel; Fig. 5 is an enlarged elevation, partly in section, of the looper and thread finger actuating means; Fig. 6 is a plan, partly in section, of the parts shown in Fig. 5; Fig. 7 is an enlarged elevation, partly in section, of the presser foot and associated parts; Fig. 8 is a detail view of the work guide; Fig. 9 is a sectional view taken on the line 9—9 of Fig. 8; Fig. 10 is an enlarged plan of the wax thread stripping device; Fig. 11 is a sectional elevation of the same; and Fig. 12 is a side elevation of one of the stripping members.

The machine illustrated in the drawings is a curved needle shoe sewing machine particularly designed for sewing the out-turned upper to the sole of a stitch-down shoe. The machine forms a chain stitch and is provided with a curved hook needle, a thread finger to measure off a length of thread between the

looper and the work, a looper to lay the thread in the hook of the needle, a take-up acting to exert a stitch setting strain on the thread while the needle is in the work, and to draw thread from the supply, and with an auxiliary take-up and a tension device, the operation of these parts being the same as in chain stitch shoe sewing machines provided with a stitch setting take-up as ordinarily constructed. During the operation of the machine the work is intermittently clamped and released by a work support and presser foot, and is fed between successive actuations of the needle by the combined action of the work support, the presser foot and a work piercing and feeding awl. In addition to these parts the machine is also provided with a stripping device for stripping wax from the thread as it emerges from the wax pot, with a work guide to engage the edge of the shoe sole, and with a brake which is operated automatically at the completion of the sewing operation to stop the machine at a predetermined point in the cycle of operations.

Referring to the drawings, the curved needle 18 is carried by a needle segment 20 which is mounted for oscillating movements on the hollow hub 22 of the needle guide which loosely embraces an extension 24 of the awl stud. The hollow hub of the needle guide is journaled in a bracket or web 26 projecting upwardly, forwardly and downwardly from the base of the machine. This web 26 forms a hollow steam heated chamber, the right hand plate-like side of which serves as a heating plate for conveying heat to various parts of the machine. The needle is actuated by a needle lever 28 pivoted on a stud 30 secured in the upper end of uprights 32 rising from the rear side of the base of the machine. The needle lever carries a stud upon which is mounted a cam roll 34 engaged by a cam path in a cam 36 mounted on the cam shaft 38. On the forward end of the needle lever is formed a segmental gear 40 which meshes with a segmental pinion formed on the needle segment 20. The arrangement of these parts and the shape of the cam path are such that the needle is actuated in timed relation with the other stitch forming members during the stitching operation.

The needle guide 42 embraces the needle and affords a support therefor in the usual

manner. The needle guide is supported for oscillating movements on its hub 22 and is actuated in timed relation with the work piercing movements of the needle by a needle guide lever 44 fulcrumed in an upward projection of the web 26. One arm of the needle guide lever carries a cam roll which is received in a cam path formed in the side of the cam 46 mounted on the cam shaft 38. The free end of the other arm of the needle guide lever is provided with a segmental gear which meshes with a segmental pinion 48 secured to or formed integral with a stud 50 pivoted in the web 26. On an extension of the hub of the segmental pinion 48 is carried a segmental gear 52 which meshes with a segmental pinion formed on the hub 22 of the needle guide.

The thread finger 54 is pivoted on a pin 56 arranged vertically in the web 26. The thread finger is actuated by a thread finger lever 58 fulcrumed on a support rising from the base of the machine. One end of the lever 58 carries a cam roll which is engaged by a peripheral cam path formed in the cam 46. The other arm of the thread finger lever is connected with an arm 60 extending rearwardly from the hub of the thread finger by means of a link 62.

The looper 64 is provided with an eye through which the thread passes and operates to loop the thread around the needle just above the barb thereof while the needle is at the limit of its downward movement. In order that the eye of the looper may be adjusted vertically and transversely relatively to the needle, the looper is provided with a stud 66. This stud, for purposes of adjustment, is received in a split collar on the outer end of an arm of a lever 68 pivoted on a crank pin 70 secured to or formed integral with a shaft 72 vertically and obliquely arranged in bearings 74 and 76 formed on the web 26. The shaft 72 is provided on its upper end with a collar 78 which rests upon the upper side of the bearing 74, and upon its lower end with a nut, which holds the shaft in operative position. The shaft 72 is actuated to impart a thread looping movement to the looper, and for this purpose is provided with a spiral slot 80 of such length and formation that, when the pin 82 which engages the slot is caused to travel upwardly the length of the slot, the shaft is turned counter-clockwise approximately one complete rotation; and when the pin 82 is caused to descend the length of the slot, the shaft is turned clockwise approximately one complete rotation. The up and down movements are imparted to the pin by a lever 84 of bellcrank form pivoted on the machine frame. On the vertically arranged arm of the lever 84 is supported a cam roll 86 which is engaged by a cam path formed in the side of the cam 36. The free

end of the horizontally arranged arm of the lever 84 is recessed axially and receives for axial movements therein the shank of a pin support 88 which loosely embraces the shaft 72. The threaded portion of the pin 82 is screwed into the front side of the pin support. The rear end of the looper lever 68 is loosely received for reciprocatory movements in a longitudinal recess in a T-shaped bearing 90 pivoted in a bracket 92 projecting laterally from the web 26. The above described construction is such that, when the shaft 72 through the actuation of the lever 84 is caused to rotate counter-clockwise, the thread eye of the looper is caused to describe an ellipse about the needle, as shown in dotted lines in Fig. 6. This movement of the looper lays the thread in the needle barb and takes place while the needle is at the limit of its downward stroke. After the needle has risen and the barb of the needle has sufficiently penetrated the work, and before the awl is again actuated to feed the work, the looper performs its return movement. It is desirable that the looper should describe a complete ellipse rather than a partial one, although it is obvious that the latter would be sufficient for the purpose of laying thread in the needle barb. The amount of movement of the looper is controlled by the throw of the cam path by which the lever 84 is actuated.

The curved awl 96 operates as is usual in this type of shoe sewing machine, and is carried by an awl segment pivoted for oscillatory movements concentric with the work piercing movements of the needle, upon an awl stud 98 journaled in a framework or feed carriage indicated generally at 100 mounted for sliding movements on a stud 102, one end of which is secured in a boss 104 on an upright rising from the machine base, and the other end of which is supported in the web 26. The extension 24 of the awl stud 98 being loosely supported in the hollow needle guide hub 22 maintains the needle and awl in concentric relation and permits the axial movements of the awl stud. The awl is actuated to pierce the work by a cam path formed on the side of the cam 106, through an awl lever 108 pivoted on the stud 110 fixed in the uprights 32. On the forward end of the awl lever is formed a segmental gear 112 which meshes with the segmental pinion 114 formed on the awl segment. After the awl has pierced the work and before it is retracted therefrom, it is actuated to feed the work to the left, viewing Fig. 1, and for this purpose the framework or feed carriage 100 upon which the awl segment is mounted, is actuated by a lever 116 mounted on a pin 118 rising vertically from the base of the machine. The rear end of the lever 116 carries a cam roll which engages a peripheral cam path in the cam 120.

The forward end of the lever 116 is provided with a slot 122 which is engaged by a roll 124 mounted on a pin 126, the shank of which is received in a slot 128 formed in the 5 lower portion of a downwardly extending bracket 130 of the feed carriage 100. The head of the pin 126 is of somewhat larger diameter than the width of the slot 128, so that the pin may be secured in adjusted position 10 on the bracket 130 by a nut screwed on the upper end of the pin. It will be observed by an inspection of Fig. 2 that when the sliding frame or feed carriage 100 is to the limit of its leftward movement, the axis 15 of the slot 128 in the bracket 130 and the axis of the slot 122 in the lever 116 are in alignment. By means of this arrangement, when the nut by which the pin 126 is secured to the bracket 130 is loosened and the 20 pin with its roll is moved rearwardly or forwardly, thereby shortening or lengthening respectively the feeding stroke, the leftward limit of movement of the feed carriage is not disturbed; so that, when the awl is at the 25 limit of its leftward movement, it is always in alignment with the needle. The feed carriage is held against rotative movement on the stud 102 by means of a rearwardly extending arm 132, the upper end of which is 30 bifurcated and loosely embraces the flattened sides of a rod 134 projecting laterally from the web 26.

The presser foot 138 is secured to an arm 140 projecting upwardly from the hub 142 pivoted on a stud 144 mounted in two uprights rising from the bosses by which the feed carriage is supported on the stud 102. The presser foot is spring actuated through 35 a vertically disposed presser foot rod 146 to automatically clamp the work on the work support 136 previous to the work piercing operation of the awl and the feeding movement of the awl and work to the left, and is cam actuated to release the work 40 to permit the parts connected with the feed carriage to return to their normal position. The upper end of the presser foot rod is loosely received in a hole in an arm 148 secured to the outer end of the rod 134, and 45 the lower end of the presser foot rod is journaled in bearings 150 and 152 in a bracket 154 secured to the machine frame. The outer end of the rod 134 is supported by the bracket 154, against which the hub of the 50 arm 148 is clamped by a nut 156. The presser foot is operatively connected with the presser foot rod by means of a segmental gear 158 formed on the hub 142 and projecting rearwardly therefrom. The gear 158 55 meshes with a rack 160 which is formed on the presser foot rod, and which reciprocates vertically in guides formed in the bracket 154. The presser foot is actuated to clamp 60 the work against the work support 136 by means of a compression spring 162 sur-

rounding the upper end of the presser foot rod. One end of the spring 162 is received in a recess in the top of the arm 148, and the other end of the spring is received in a recess in a collar 164 on the upper end of the presser foot rod, the collar being held 70 in position by check nuts 166 threaded on the end of the presser foot rod. By means of these check nuts the tension of the spring 162 may be regulated, and thereby the force 75 with which the presser foot clamps the work on the work support may be varied as desired. When the presser foot has been actuated to clamp the work on the work support, it is locked in this position by a 80 lock mechanism, so that any upwardly directed force tending to lift the presser foot acts, not against a yielding spring, but against a positive lock. This lock mechanism comprises a lock lever 168 consisting of two 85 arms fulcrumed at their forward ends on a pivot 170 fixed in the bracket 154. Located rearwardly of the pivot 170 is a lock roll 172 pivoted on a pin fixed in the arms of the lever 168. When the rearward end of the lock lever is raised, the lock roll 172 is 90 forced against the periphery of a lock nut 174 provided with a thread of a steep pitch, which is received on a correspondingly pitched thread on the presser foot rod. 95 When the lock roll is jammed against the periphery of the lock nut, the presser foot rod is held against vertical movements, but when the lock roll is moved out of contact with the lock nut, the presser foot rod may 100 be raised or lowered. During the vertical movements of the presser foot rod in either direction the lock nut rotates, the pitch of the screw permitting relative movement between the lock nut and the presser foot rod 105 by either an upward or downward pressure on the rod. The rearward end of the lock lever 168 is moved upwardly to force the lock roll against the lock nut by means of a presser foot lever 176 pivoted at its rearward end on the stud 110. The presser foot lever 176 carries a cam roll which engages a cam path formed in the side of the cam 110 166. The forward end of the lever 176 is pivoted to a two armed link 178, the lower arm of which is pivoted to the rearward end of the lock lever 168, and the upper arm of which is pivoted to a clamping lever 180 fulcrumed at its forward end in ears formed on a sleeve 182 which loosely embraces the 115 presser foot rod. A spring interposed between the bottom end of the sleeve 182 and the bearing 150 tends to maintain the sleeve in raised position. The forward end of the clamping lever 180 is provided with a pinch 120 cam, which is adapted at certain times during the operation of the machine, to engage the presser foot rod and lock the sleeve 182 to it. While the presser foot is in operative position clamping the work on the work 125 130

support, the cam of the clamping lever is out of engagement with the presser foot rod, and the lock roll is in engagement with the lock nut. After the feeding movement 5 of the feed carriage and the parts supported thereon is completed, so that the awl is in alignment with the needle and the needle has penetrated the work, the presser foot lever 176 is actuated by its cam path so that 10 its forward end is moved downward to disengage the lock roll 172 from the lock nut 174 and to press the cam of the clamping lever 180 against the presser foot rod. The continued downward movement of the forward end of the presser foot lever causes 15 the presser foot rod to be carried downwardly, thereby lifting the presser foot out of engagement with the work on the work support. The movement of the presser foot 20 away from the work is such that the work support and the presser foot may be moved relatively to the work while it is held by the needle, without rubbing the work injuriously or catching on a thick place so as 25 thereby to exert a strain on the needle. After the stitch forming operation is completed and the shoe is to be removed from the work support, the presser foot lever 176 is in such position that the clamping lever 30 180 is neither in engagement with the presser foot rod nor the lock roll in engagement with the lock nut. Consequently when the operator presses a treadle connected with the bottom end of the presser foot rod 146, 35 the rod will descend and the presser foot be lifted from the work. If the presser foot rod treadle is released while there is no work on the work support and the spring 162 is permitted to actuate the presser foot 40 and move it toward the work support, a sleeve 184 loosely received on the presser foot rod and supported thereon by nuts 186 will be brought into engagement with an adjustable stop 188 (see Fig. 1) by the upward movement of the rod 146 and thereby 45 prevent the presser foot from coming into contact with the work support. The construction and arrangement of the presser foot and its associated parts are such that 50 work of different thicknesses may be clamped on the work support and the variation in thicknesses automatically compensated for.

The work support 136 is secured to the 55 feed carriage, and is provided with the usual slot for the reception of the awl and the needle during the stitch forming operation.

The work guide 190 is secured on the upper end of an arm 192 having a bifurcated hub 194 which loosely embraces the stud 102. Projecting rearwardly from the bifurcated hub 194 of the arm 192 is an arm 196 to which is pivoted the upper end of a 65 rod 198, the lower end of which is con-

nected to a treadle for the purpose of permitting the operator to move the work guide rearwardly from its forward position, which normally determines the width of the seam, so as to accommodate a vamp which projects outwardly beyond the edge of the sole to which the vamp is being attached. The work guide is held in operative position by means of a plunger 200 housed in a chamber 202 formed on a ring 204 pinned to the stud 102 between the sides of the bifurcated hub 194 of the work guide arm 192. A compression spring tends to force the plunger 200 against a shoulder formed on the rearwardly projecting arm 196. A screw 206 threaded in the closed end of the chamber 202 limits the amount of rearward throw of the work guide by engaging the head of the plunger 200. This spring is of sufficient tension to maintain the work guide 70 in operative position while the operator holds the work against it. The width of the margin formed during the stitching operation is regulated by regulating a screw 208 received in a threaded hole in the split 75 end of an arm 210 extending upwardly from the ring 204. The screw 212 clamps the regulating screw in adjusted position.

The take-up comprises a take-up thread truck 214 carried on the outer end of a take-up arm 216 of a bellcrank lever, the hub 218 of which is fulcrumed on a hollow stud 220 journaled in bearings formed in arms projecting forwardly from a bracket secured to the machine frame. The other arm 222 100 of the bellcrank lever is connected by a link 224 to the slotted lower end of an arm 226 of a take-up lever of bell-crank form pivoted at 228 on an upright rising from the base of the machine. The other arm of the take-up lever extends rearwardly and carries a cam roll which engages a cam path formed in the outer side of the cam 120. As the thread is drawn from the wax pot 232 it passes over a roll 234, thence around a large thread truck or tension wheel 236 mounted on a shaft 238 supported in the hollow stud 220, and thence over two small pulleys or thread trucks 240 and 242, which form part of the auxiliary take-up, to the truck 214, from whence it passes under the truck 244 to the looper. The auxiliary take-up comprises a lever 246 pivoted at 248 on the machine frame, and on one end supports a pin on which the thread truck 242 is pivoted. The other end of the auxiliary take-up lever receives one end of a lightly tensioned spring 250, the other end of which is secured to the machine frame. A secondary compression spring 252, more heavily tensioned than the spring 250, is received in a chamber 254 formed on the machine frame, one end of the spring 252 pressing against a shoulder of a plunger 256 adapted to reciprocate in the chamber 254 and the other end of the spring 110 115 120 125 130

taking against a nut 258 threaded in the open end of the chamber. The nut 258 affords means by which the tension of the spring 252 may be regulated. The movement of the auxiliary take-up lever 246 under the force of the spring 250 is limited by a stop pin 260.

It will be observed from an inspection of Figs. 1 and 3 that the tension wheel 236 and the thread trucks of the take-up and auxiliary take-up as well as the truck 244 are located and operate in close proximity to the heating plate forming the right hand wall or surface of the heated chamber or web 26. By means of this construction the radiation from the heating plate keeps the waxed thread as it passes over the trucks on its way to the needle in a pliable and easily workable condition.

20 In addition to the tension wheel 236, the tension mechanism comprises a brake strap 262 which makes one complete turn around a drum 264 fast on the outer end of the shaft 238, on the other end of which the tension wheel 236 is fixed. One end of the brake strap is secured to the frame of the machine, and the other end is secured to an eye of a bolt 266 loosely received in a hole in a tension lever 268 pivoted on the machine frame. By arranging the brake strap so that it makes one complete turn around the drum 264, the lines of stress upon its ends act in opposite directions. The free end of the tension lever 268 is bifurcated and loosely embraces the presser foot rod 146. A heavy compression spring 270 interposed between the under side of the lever 268 and a projection upon the base of the machine, holds the free end of the lever 268, during 40 the stitch forming operation, against a stop bolt 272 passed through a threaded hole in a lug extending laterally from the machine frame. The operative position of the free end of the lever 268 may be adjusted vertically by means of the bolt 272. A compression spring 274 encircling the upper end of the bolt 266 and secured in position thereon by a nut, by which the tension of the spring 274 may be regulated, tends to maintain the

50 bolt 266 in raised position and imposes on the brake strap the strain requisite to maintain the required amount of tension on the thread. It will be observed by the construction and arrangement of the parts of the 55 tension device that the pull exerted upon the brake strap is such that no cramping strain is imposed upon the shaft 238 because the strain is evenly distributed over the periphery of the pulley 264, and yet an effective 60 clamping strain or gripping action is imposed upon the shaft 238 and the tension wheel 236. The relative arrangement of the tension lever 268 and the presser foot rod is such that, when the operator presses the 65 treadle connected with the presser foot rod,

upon the completion of the sewing operation, the downward movement of the presser foot rod brings the nuts 276 threaded on the rod into engagement with the upper surface of the free end of the tension lever, 70 thereby depressing it against the upward action of the spring 270 and relieving the tension strap of the strain of the spring 274 to permit the operator to remove the shoe with the thread attached to it from the machine. The space between the nuts 276 and the upper side of the free end of the tension lever is such that, when at the completion of each feeding movement the presser foot rod descends and the presser foot is raised 80 to permit the return of the feed carriage, the nuts do not come into contact with the tension lever, and, consequently, the uniform tension exerted by the tension device is not disturbed.

As the thread is drawn from the wax pot 232 it passes through a stripping device consisting of two triangularly shaped spring-like stripping members 280 and 282, which are so arranged when in operative position 90 that their inner corners interlock, as shown in Fig. 10. The space enclosed between the interlocking corners of the stripping members and through which the thread passes may be regulated to leave any desired 95 amount of wax on the thread, by means of an adjustment block 284 pressed against the stripping members by means of a screw 286 received in a boss formed on the housing or chamber 288 in which the stripping members 100 are located. The forward wall of the housing or chamber 288 projects inwardly and is V-shaped in cross-section, one side of each stripping member resting against one side of this V-shaped wall respectively. When 105 the corners of the stripping members in operative position become worn, two fresh corners may be used in their place, and when these in their turn become worn, the two remaining corners may be used. It is thus 110 seen that the present construction of stripper is highly efficient and economical and may be employed in any type of shoe sewing machine.

During the operation of the machine the 115 operator keeps his foot upon a stopping and starting treadle to which is connected the lower end of a rod 290. Upon the completion of the stitching operation the operator releases the treadle, and thereby disconnects 120 the machine from its source of power in the usual manner and at the same time allows the rod 290 to move upwardly. Upon the upper end of the rod 290 are pivoted the two arms or links 292 and 294 of a toggle joint. 125 The toggle joint arm 292 is pivotally connected with a downwardly extending arm 296 of a bellcrank lever 298 pivoted on the stud 110. The free end of the upwardly extending arm 300 of this bellcrank lever 130

carries a cam roll which engages a cam path formed in the side of the cam 46. The toggle joint arm 294 is pivotally connected with the lower end of a downwardly extending 5 arm 302 of a bellcrank lever 304 also pivoted on the stud 110. Between the sides of the bifurcated free end of an upwardly extending arm 306 of the bellcrank lever 304 is mounted a brake shoe 308. A slot formed in 10 a rearwardly extending part of the brake shoe engages a bolt 310 passing through holes in the bifurcated end of the arm 306. The brake shoe is provided with a set screw 312, by which it may be adjusted relatively 15 to the cam 46. The bolt 310 secures the shoe in adjusted position. While the toggle joint is open, as shown in Fig. 3, the actuations imparted to the bellcrank lever 298 by the cam 46 are not effective to bring the brake shoe against the periphery of the cam 46. But when the operator releases the treadle and the upward movement of the rod 290 under the actuation of its spring closes the 20 toggle joint, that is, brings the arms 292 and 294 into longitudinal alignment, the rearward oscillatory movement of the arm 296 of the bellcrank lever 298 causes the brake shoe to be clamped against the periphery of the cam 46. This preliminary engagement of the brake shoe with the cam is 25 not sufficient to stop the machine, but as the cam shaft continues to rotate, the needle is brought to the limit of its upward stroke and the awl is brought to the limit of its 30 downward stroke; and by the time the needle and awl reach these positions, the cam roll on the arm 300 is engaged by the cam path at its least radial distance, whereupon the brake shoe is caused to exert a powerful 35 grip on the periphery of the cam 46 and thereby stop the machine.

The operation of the machine has been indicated in the description already given of the construction and arrangement of its various parts and will be readily understood 45 by those skilled in the art without a separate description thereof.

The thread tension devices, the looper mechanism and the thread waxing devices 50 disclosed in the present application form the subject matter of divisional applications filed November 21, 1919, Serial Nos. 339,649, 339,650, and 339,651.

The nature and scope of the present invention 55 having been indicated and a machine embodying the several features of the present invention in their preferred form having been specifically described, what is claimed is:

60 1. A shoe sewing machine having, in combination, stitch forming devices, work feeding means, a work support, a presser foot, a presser foot rod yieldingly actuated in one direction and positively actuated in the other direction, connections between the presser

foot and the presser foot rod permitting relative transverse movement between them, and connections between the work feeding means and the presser foot.

2. A shoe sewing machine having, in combination, 70 a work support and a presser foot arranged to receive the projecting edge of the outsole of a shoe between them, a needle, an awl, means for moving the awl, the presser foot and the work support to feed the work, and means to separate the work support and the presser foot and to return them and the awl while the needle is in the work.

3. A shoe sewing machine having, in combination, 80 a work support and a presser foot arranged to receive the projecting edge of the outsole of a shoe between them, a needle, an awl, means for moving the awl, the presser foot and the work support to feed the work, and means to return the work support, presser foot and the awl together, while the needle is in the work.

4. A shoe sewing machine, having, in combination, 90 stitch forming devices, a work support, a presser foot, a rod, actuating connections between the rod and presser foot, a spring acting on the rod to force the presser foot against the work, and mechanism for locking the presser foot in position comprising 95 a nut threaded on the rod, and means for locking the nut against rotation.

5. A shoe sewing machine, having, in combination, 100 stitch forming devices, a work support, a presser foot, a rod, actuating connections between the rod and the presser foot, a spring acting on the rod to force the presser foot against the work, means for moving the rod to raise the presser foot from the work, and mechanism for locking the presser foot 105 in position on the work comprising a nut threaded on the rod, and means for locking the nut against rotation.

6. A shoe sewing machine, having, in combination, 110 stitch forming devices, a work support, a presser foot, a presser foot lever on which the presser foot is mounted, a rod, a spring acting on the rod to force the presser foot against the work, a locking device engaging the rod, and means for actuating the 115 locking device to lock and unlock the presser foot during each cycle of operations of the machine.

7. A shoe sewing machine, having, in combination, 120 stitch forming devices, a work support, a presser foot, a presser foot lever on which the presser foot is mounted, a rod, actuating connections between the rod and the presser foot lever, a spring acting on the rod to force the presser foot against the work, a lever provided with a pinch cam engaging the rod, and means for actuating said lever to move the rod in a direction to raise the presser foot.

8. A shoe sewing machine, having, in com- 130

bination, stitch forming devices, a work support, a presser foot, a presser foot lever on which the presser foot is mounted, a rod, actuating connections between the rod and the 5 presser foot lever, a spring acting on the rod to force the presser foot against the work, a presser foot lifting lever provided with a pinch cam engaging the rod, means for actuating said lever, and means for locking the 10 rod against movement while the presser foot is in contact with the work.

9. A shoe sewing machine, having, in combination, stitch forming devices, a work support, a presser foot, a presser foot lever on 15 which the presser foot is mounted, a rod, actuating connections between the rod and the presser foot lever, a spring acting on the rod to force the presser foot against the work, a presser foot lifting lever provided with a 20 pinch cam engaging the rod, and a presser foot locking device comprising a nut threaded on the rod, and means for locking the nut against rotation.

10. A shoe sewing machine, having, in 25 combination, stitch forming devices, a work support, a presser foot, a rod, actuating connections between the rod and the presser foot, a spring acting on the rod to force the presser foot against the work, a presser foot 30 lifting device engaging the rod, a locking device engaging the rod, an actuating lever and connections between said lever and the lifting and locking devices for actuating said devices to unlock and lift the presser foot 35 when the lever moves in one direction, and to release and then lock the presser foot

when the lever is moved in the other direction.

11. A shoe sewing machine, having, in combination, stitch forming devices, a work 40 support, a feed slide, a presser foot lever mounted on the feed slide, a rod mounted in the frame of the machine, a toothed segment and rack connection between said rod and the presser foot lever, and means acting on 45 the rod to force the presser foot against the work.

12. A shoe sewing machine, having, in combination, a work support and a presser foot arranged to receive the projecting edge 50 of the outsole of a shoe between them, a needle and an awl, said work support, presser foot and awl being movable in the line of feed.

13. A shoe sewing machine, having, in 55 combination, a work support and a presser foot arranged to receive the projecting edge of the outsole of a shoe between them, a needle and an awl one of which acts as the feeding instrument, said work support and 60 presser foot being movable in the line of feed with the feeding instrument while said instrument is in the work.

14. A shoe sewing machine, having, in combination, a work support and a presser 65 foot arranged to receive the projecting edge of the outsole of a shoe between them, a needle, an awl and a feed slide, said work support, presser foot and awl being mounted on the feed slide.

FREDERIC E. BERTRAND.
